(57) **CLAIM**

The ornamental design for the dust mop head, as shown and described.

DESCRIPTION

FIG. 1 is a perspective view of a dust mop head showing the new design;

FIG. 2 is a front view of the dust mop head as shown in FIG. 1;

FIG. 3 is a rear view of the dust mop head as shown in FIG. 1;

FIG. 4 is a right side view of the dust mop head as shown in FIG. 1;

FIG. 5 is a left side view of the dust mop head as shown in FIG. 1;

FIG. 6 is a top view of the dust mop head as shown in FIG. 1;

FIG. 7 is a bottom view of the dust mop head as shown in FIG. 1;

FIG. 8 is a perspective view of the dust mop head of FIG. 1 shown in an open configuration;

FIG. 9 is a front view of the dust mop head as shown in FIG. 8;

FIG. 10 is a rear view of the dust mop head as shown in FIG. 8;

FIG. 11 is a right side view of the dust mop head as shown in FIG. 8;

FIG. 12 is a left side view of the dust mop head as shown in FIG. 8;

FIG. 13 is a top view of the dust mop head as shown in FIG. 8; and,

FIG. 14 is a bottom view of the dust mop head as shown in FIG. 8.

Components in the appended drawings shown in broken lines are considered environment and form no part of the claimed design.

1 Claim, 13 Drawing Sheets
